HEAT EXCHANGER FRAMING FOR
METAL BOATS

Newman C. Jannsen, Seattle, Wash.

Application April 7, 1947, Serial No. 739,982

3 Claims. (Cl. 115—0.5)

1

My present invention relates to the general art of heat exchangers and, more particularly, to a heat exchanger framing for metal boats.

During the period recently past, the greatly amplified boat building program incidental to the recent war advanced the technique of welding boats to such an extent that it is now, for the first time, practical to build the smaller types of cabin boats of metal. Formerly, it was considered good practice to weld the framing and plating of seagoing ships, but the building of small craft presented so many problems in shrinkage and distortion of the various welded members, that it did not appear practical to employ such construction in boats of even 100 ft. in overall length, and especially in the smaller sizes.

Due, however, to the great strides made in perfecting welding technique and further by adoption particularly of the tubular framing members as is illustrated in my copending application Serial No. 480,897, which matured into United States Patent No. 2,419,218, it is now entirely practical to build the smaller types of fishing craft, tow boats, and small carriers of freight and passengers, and even the smaller types of pleasure craft, both sail and powered.

The adoption of tubular framing members not only has greatly simplified the shrinkage problems and the attendant distortion of the plate and structural members, but has provided a very economical and fool-proof manner of providing a heat exchanger so that the cold waters in which the boat is travelling can be used to dissipate the heat generated in the cooling water of the internal combustion engines used to propel such boats.

In the older craft used for fishing and in small boat constructions where wood was the favorite building material, it was customary to use what was commonly known as a heavy duty type of engines. These were large masses of cast iron, which due to their bulk and the thick walls of the engine cylinders, heads and other parts requiring cooling, could accept the sea water as a cooling medium. However, the commercial trade has become conscious of the savings to be made in employing high speed engines in such craft, and as these place quite a premium on weight and are normally made, horse power for horse power, to weigh but a fraction of the total weight of the heavy-duty types formerly used, it has been found most desirable to employ a neutral fresh water coolant so that the thin walls and small passageways will not be obstructed, nor

2

will corrosion and rusting and possible electrolytic action tend to eat out the relatively thin walls of those portions of the engine that require cooling.

5 It is to provide a solution of the needs brought about by these revolutionary changes in small boat construction that I have provided my novel framing and heat exchanger.

The principal object of my invention, therefore, is to provide, in a fabricated metal boat, a plurality of tubular members running lengthwise of the boat, and which take the place of and provide the strength formerly assured by the use of a keel, stringers, bilge keels, and the like, and to further use these same tubular members as a heat exchanger so that a neutral fresh water may be used as a coolant for the internal combustion engines.

A further object of my present invention is 20 to provide longitudinally disposed tubular members within the structural framework of the metal boat which are in intimate contact with the waters through which the boat sails and which, by this contact, make it possible to efficiently cool engine coolants which are passed through the tubular members in a closed circuit arrangement.

A further object of my present invention is 25 to provide a plurality of longitudinal, tubular, structural members as part of a ship's framing, so disposed that one or more of these tubular members may be used as heat exchangers and thus provide a degree of cooling for the engine coolant that can be adjusted easily to the temperatures desired and the temperatures of the water in which the ship is sailing.

Further objects, advantages and capabilities 30 will be apparent from the description and disclosure in the drawings or may be comprehended or are inherent in the device.

40 In the drawings:

Fig. 1 is a vertical, longitudinal view through a metal ship, partly in section, incorporating the features of my present invention.

45 Fig. 2 is a typical cross-sectional view through the ship of Fig. 1.

Fig. 3 is a typical cross-sectional view showing in fragmentary perspective a typical use of my longitudinal tubular frame members.

50 Fig. 4 is a diagrammatic view showing the general arrangement of my tubular frame members and the valve means which permits selection of sufficient cooling area to meet operating conditions.

55 Referring more particularly to the disclosure

in the drawings, the numeral 10 designates my main structural member. This normally is a tube of appreciable diameter, and provides the upright portion 12 which forms the stem or cut-water of the boat, as well as a structural member, and the horizontal member 14, which serves as a keel for the boat in addition to tying together the various structural members.

In the illustration in Fig. 1, I have shown the outgoing cooling water pipe 46 as connecting into the stem 12, and have shown a return pipe 18 as tapping into the keel near its rearmost end, and leading from that point into a reservoir 20 and thence from the reservoir through pipe 22 into the intake for the cooling water of the engine. This in effect forms a closed circuit in which any form of coolant may be used for the internal combustion motor M such as fresh water, either in its natural state or neutralized, or it will take the various non-freezing coolants which are so desirable in boats that are used under conditions where they may be laid up or are idle for extended periods in a climate where low temperatures may be expected. The reserve or supply tank 20 for the coolant should have sufficient upward extent so that it will be the high point in the cooling water system, so that it may be vented to atmosphere and will at all times insure that the cooling circuit will be entirely filled and free from air pockets. In the illustration, I have shown a deck fill pipe for tank 20 as at 24. This filling pipe should be of considerable diameter so that of itself it will augment the storage capacity or reserve supply of coolant and provide an easy means of determining when any appreciable amount of coolant has been dissipated through loss or otherwise. It also provides, following hydrostatic principles, the required head on the system even though it may be of relatively small diameter.

In the illustration in Fig. 1, I have for the sake of clarity shown only one complete circuit and that of rather large diameter tubing. It is believed that it will be apparent that such an arrangement would be satisfactory only where the cooling needs of the engine are not great and where the water through which the ship is passing is quite cool.

There are other conditions encountered, particularly off our southern coast, where the water temperatures may be quite high and the normal air temperatures, particularly in the tropics, may be so high that, on the one hand, the motor will require considerably more cooling and, on the other hand, the heat exchanging system is not capable of dropping the temperature sufficiently with the limited surface exposed in the showing of Fig. 1. To overcome this condition, I have provided suitable connections to other longitudinal tubular frame members as 26, 28, 30 and 32, so that additional cooling surfaces are presented to the ship supporting waters and the engineer in charge of the power plant may, by proper manipulation of the valve means, use as many of the tubular members as is required to give him the overall transfer of heat required to satisfy his power plant. This has been found a matter of considerable importance as the ship that is fishing for tuna and other warm water fish may cruise down as far as the equator in quest of the same and, at other seasons of the year, may be used in Alaska and, similarly on the east coast, the same boat may within a year's time be used in warm southern or the cold northern waters and it is imperative that adequate provision be made so that the cooling needs of the motor can

be satisfied by the exposed framing built into the ship if a heat transfer system following the principles of my invention is going to have practical commercial application.

It will be clear it is believed from a study of Fig. 3 of the drawing that the hull plating sections as 34 and 36 are butt welded to the tubular frame member as 38 which might be any of the longitudinal members shown in Fig. 2. As expansion and contraction occurs, either during the fabrication of the ship or while the same is in use, following principles that are well known, the steel tubing which I prefer to use and which should be generally of the character of steel boiler tubing as far as composition of metal is concerned, is capable of considerable distortion in cross-section. It may be elongated if placed under tension, or it may be flattened if placed under compression, and may be subjected to the two extremes many times without any detrimental effects to the framing. Such distortion of the tubing will cause some decrease in the carrying capacity or the cross-sectional area of the tubing but, then again, if the distortion should interfere and reduce the heat transfer capacity of the tubing below that required by the power plant, additional tubing can be cut into the service and correct the fault.

In Fig. 4, I have illustrated, diagrammatically, one satisfactory valve and tubing arrangement for the combined use of framing the heat exchange means and for framing a metal boat. It is to be noted that each tube has half of its periphery exposed to the cooling water, as shown in Fig. 3, and in addition the fact that the shell plating is butt welded to the tube greatly augments the cooling effect upon the engine coolant circulating through the tubing.

I find it desirable to use a plurality of valves as 40, 41, 42 and 43, and a number of cross connection tubes as 45, 46, 47, 48 and 49, together with a transom tube frame 50 which joins the various frame members together.

With the valve and connector arrangement noted, many different combinations are possible, so that the coolant being circulated by pump 52 may have a short path, or the length of the flow may be increased by cutting in more frame tubes until adequate cooling is achieved. The use of frame tubing, because of the large diameter, offers little resistance to the flow of the coolant, in contrast to the tortuous path provided in most heat-exchanger units.

It is believed that it will be clearly apparent from the above description and the disclosure in the drawings that the invention comprehends a novel construction of a heat exchanger framing for metal boats.

Having thus described my invention, I claim:

1. A heat exchanger framing for welded metal boats, comprising: a tubular keel member, a plurality of longitudinal tubular frame members disposed substantially equidistant from said keel member, shell plating disposed between said frame members and welded to diametrically opposite portions of each frame member to expose substantially half of the surface of each frame member as the outer skin of the boat, tubular connectors disposed between said tubular members and interconnected with said tubular members, and valve means disposed in said tubular members and connectors to provide liquid passageways of various lengths.
2. Longitudinal framing for welded metal boats, adapted to form a heat exchange for pro-

75

pulsion engine coolants, consisting of: a tubular keel member, a plurality of longitudinal tubular frame members disposed substantially equidistant from said keel member, shell plating disposed between said tubular members with the longitudinal edges of said shell plating welded to substantially diametrically opposite portions of each tubular member, whereby said keel member and said frame members are positioned to expose substantially half of their surface as the outer skin of the boat, tubular connectors disposed between said tubular keel and frame members and interconnected with said tubular keel and said frame members, and valves positioned in said tubular members and connectors to control flow of liquid in said tubular members and connectors to provide liquid passageways of various lengths.

3. Longitudinal framing for welded metal boats, adapted to form a heat exchange for propulsion engine coolants, comprising: a tubular keel and stem member; a plurality of longitudinal tubular frame members disposed on each side of said keel member having their forward ends connected to the stem portion of said tubular keel and stem member; tubular connectors disposed between said tubular members and inter-

connected with said tubular members; shell plating positioned between said tubular members having the longitudinal edges of said shell plating butt-welded to opposite sides of said tubular members, whereby substantially half of the surface of said tubular members is exposed as the outer skin of the boat; and valves positioned at various junctures of tubular members and connectors, providing means of varying the length of tubular members and connectors.

10 NEWMAN C. JANSEN.
